US00D924560S

(12) **United States Design Patent** (10) **Patent No.:** **US D924,560 S**
(45) **Date of Patent:** **** Jul. 13, 2021**

(54) **CASE FOR EARPHONES**

(71) Applicant: **SPIGEN KOREA CO., LTD.**, Seoul (KR)

(72) Inventor: **Young Kwang Hyun**, Seoul (KR)

(73) Assignee: **SPIGEN KOREA CO., LTD.**, Seoul (KR)

(**) Term: **15 Years**

(21) Appl. No.: **29/713,915**

(22) Filed: **Nov. 19, 2019**

(51) LOC (13) Cl. **03-01**

(52) U.S. Cl.

USPC **D3/218; D3/302**

(58) **Field of Classification Search**

USPC D3/201, 203.1, 204, 205, 207–208, 212, D3/215, 218, 269, 273–274, 276, 283, D3/284, 294–300, 302, 303, 315, 901, D3/903; D9/414, 418, 420, 430, 432; D28/66, 73, 76, 78, 91; D14/188, 201, D14/204, 205, 209.1, 217, 250, 251, 440, D14/447

(57) **CLAIM**

The ornamental design for a case for earphones, as shown and described.

DESCRIPTION

FIG. 1 is a front perspective view of a case for earphones showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded front perspective view of the case for earphones, showing the components separated for clarity of disclosure.

The dot dash broken lines depict a boundary of the claimed design and form no part thereof. The dash-dash broken lines depict portions of the case for earphones that form no part of the claimed design.

1 Claim, 9 Drawing Sheets
